UNITED STATES PATENT OFFICE.

WILLIAM L. FOSTER AND HARRY J. WILLIAMS, OF DAYTON, OHIO.

CASEMENT-ADJUSTER.

1,146,241.

Specification of Letters Patent.

Patented July 13, 1915.

Application filed March 18, 1915. Serial No. 15,360.

To all whom it may concern:

Be it known that we, WILLIAM L. FOSTER and HARRY J. WILLIAMS, citizens of the United States, residing at Dayton, in the 5 county of Montgomery and State of Ohio, have invented certain new and useful Improvements in Casement-Adjusters, of which the following is a specification, reference being had therein to the accompanying drawings.

This invention relates to casement adjusters.

The object of the invention is to provide a device of this kind which will be practically concealed, thereby avoiding all unsightly attachments or projections from the window sash sill or frame; which will not require any special sash or frame construction; which will not interfere with screens 20 or blinds; which will be of a strong, durable character and the locking mechanism of which will be such as to make it practically impossible to injure the device by attempts to move the sash when the device is locked; which can be adapted to right or left swing for use either with an inwardly swinging or an outwardly swinging sash; and which can be quickly and easily applied to the window.

30 In the accompanying drawings, Figure 1 is a perspective view of a window frame and sash equipped with our invention; Fig. 2 is a vertical, sectional view taken through the sill and the lower portion of the sash of such a window; Fig. 3 is a horizontal, sectional view taken through the adjuster on the line $x-x$ of Fig. 2; Fig. 4 is a horizontal, sectional view taken through the adjuster on the line $y-y$ of Fig. 2; and Fig. 5 is a vertical section taken through the sill and the lower part of the sash showing the adjuster applied to an inwardly swinging sash.

In these drawings we have illustrated one embodiment of our invention and have 45 shown the same as applied to a hinged window sash mounted in an ordinary window frame but it will be understood that the invention is not limited in its utility to swinging windows but that it may be utilized for 50 controlling the adjustment of any hinged member relatively to a fixed supporting member.

In Figs. 1 and 2 we have shown the window frame, at 1, as having hinged thereto 55 an outwardly swinging sash 2 of ordinary construction. The window frame includes the usual inner sill 3 and outer sill 4 and it

will be understood that these parts may be of any suitable construction. Rigidly secured to the frame and preferably let 60 into the outer sill 4 is a guide 5 which is here shown as a plate provided with an elongated slot. This plate extends lengthwise of the sill and the sill is preferably cut away beneath the guide slot to form a 65 groove 6. Mounted on the sash, and preferably let into the lower rail thereof, is a locking device, which, in the form here shown, comprises a plate 7 having secured to the inner face thereof and, in the present instance, formed integral therewith, a socket 8 which forms a vertical bearing. The socket is preferably mounted in a recess 9 formed in the sash rail, while the plate bears against the outer face of the rail and is secured thereto by screws or in any other suitable manner. Mounted in the bearing or socket 8 is a pivot pin or stud 10 having rigidly secured to the lower end thereof one 70 end of an arm 11, the opposite end of which is provided with a stud 12 extending through the slot in the guide plate 5 and having a head 13 which lies in the groove 6 beneath the guide plate and serves to retain the stud in the guide slot, it being understood 75 that the groove 6 is of greater width than the slot in the guide plate, thereby permitting the head to overlap the edges of the slot. The stud may be placed in the slot in any suitable manner, as by flattening the 80 sides of the head 13 transversely to the length of the arm, in a well known manner. The bottom of the lower sash rail is cut away, as shown at 14, to provide a recess to receive the arm 11 when the sash is moved 85 to its closed position, at which time the arm 11, the guide plate 5 and the lower sash rail are arranged substantially parallel one to the other, as shown in Fig. 2. It will be apparent that as the sash is swung on its 90 hinges the arm will move about its pivotal mounting in the sash rail and that the stud 12 of the arm will be guided in a fixed line along the outer sill of the window frame by the guide plate 5 with which it cooperates.

To hold the sash in any given position we have provided means for locking the stud 8 against pivotal movement in its bearing, thereby holding the arm 11 in fixed relation 110 to the sash, causing the arm to extend at an angle to the guide slot and thus locking the sash against movement. While this locking of the pivot pin may be accomplished in dif-

ferent ways that here illustrated has proven very efficient in operation. In the present device the socket or vertical bearing 8 is in the form of a split sleeve, the side wall of the bearing being slotted throughout its length, as indicated at 15. Secured to the outer portion of the sleeve is a lug 16 into which is screw-threaded a stem 17 which projects through the face plate 7 of the structure and is provided on its outer end with a milled head 18, by means of which it may be rotated. The hub of this head 18 bears against the face plate and serves to limit the inward movement of the stem. Consequently, when the head is rotated to screw the stem into the lug 16 this lug and that portion of the split sleeve to which it is attached are drawn toward the face plate, thereby contracting the bearing opening within the sleeve and exerting a powerful clamping action upon the pivot pin. This clamping action is such as to effectually hold the arm against movement relatively to the sash, and further is of such a character that no injury can be done if pressure is applied to the edge of the sash in an effort to move the same while the pivot pin is locked against movement. If the pressure is sufficient to overcome the frictional contact between the pins and the walls of the socket the arm will yield, but the arrangement of the parts is such that this pressure would throw but little strain upon any part of the device which is liable to be strained or broken. Consequently, the device is in this respect fool proof.

The device is readily adaptable for use with either an inwardly swinging sash or an outwardly swinging sash. In Figs. 1 and 2 the sash swings outwardly and the inner portion of the bottom sash rail is cut away, thus exposing the edge of the arm 11 when it lies within the recess. When the sash is in its closed position this recess is concealed by the inner sill 3 against the edge of which the sash rail bears. It will be noted that in this arrangement of the device the end of the pivot pin 10 which is connected with the arm 11 projects beyond the lower end of the socket 8 and the lower edge of the face plate 7 is substantially flush with the upper edge of the recess 14 in the sash rail, this being necessary to permit the movement of the arm across the plane of the face plate 7.

In Fig. 5 we have shown the device as applied to an inwardly swinging sash. Here the pivot pin has its lower end substantially flush with the lower end of the socket and the arm 11 lies back of and is concealed by the face plate 7. Because the arm moves across the outer edge of the sash rail instead of the inner edge thereof it is not necessary to cut away or recess the sash rail on its inner side. Consequently, the arm is not exposed and the only portion of the fixture

visible from the inside of the window is the face plate 7 and the locking knob 18. The operation here is exactly the same as that described in connection with the outwardly swinging sash.

To permit of the same fixture being used with either an inwardly or outwardly swinging sash means are provided for securing the pivot pin in either one of two positions. To this end it is provided with two circumferential grooves 19 spaced one above the other and the socket or bearing block is provided with a recess 20 which intersects the bearing and is adapted to receive a pin 21, the outer portion of which is screw-threaded, as shown at 22, to enable it to be screwed into the opening 20. Before the pin can be inserted the pivot pin 10 must be moved into such a position as to bring one of the grooves 19 into alinement with the opening 20. The pin then extends through a portion of that groove 19 which is in alinement with the opening 20 and thereby locks the pivot pin against axial movement without interfering with its rotary movement. By arranging the pivot pin so that the lower groove 19 will receive the pin 21 the lower end of the pivot pin is held flush with the lower end of the socket, as shown in Fig. 5. When the pivot pin is arranged to permit the pin 21 to enter the upper groove 19 the lower end of the pivot pin projects below the lower end of the socket, as shown in Fig. 2. This adjustment is a very simple one and can be quickly and easily made and it is the only change that it is necessary to make in the device to change it from an adjuster for an inwardly swinging sash to an adjuster for an outwardly swinging sash. The only other change is in connection with the installation of the device. In the case of the inwardly swinging sash the recess to receive the arm 11 must be formed in the outer edge of the sash rail instead of the inner edge thereof. The face plate 7 and the bearing socket 8 are mounted on the inner side of the sash rail in both instances.

The operation of the device will be readily understood from the foregoing description and it will be apparent that we have provided an adjusting device of this kind which is not only applicable to hinged window sash but to hinged members of various kinds regardless of the direction in which they swing; which is very simple and very strong in its construction; and which has a powerful locking action which will effectually hold the sash in its adjusted positions.

While we have shown and described one embodiment of the invention it will be understood that this has been chosen for the purposes of illustration only, and that we do not desire to be limited to the details of construction shown and described, for obvious modifications will occur to a person skilled

in the art. For example, while the guide plate rigidly secured to and extending lengthwise of the sill, has important advantages over any other form of connection 5 with which we are now familiar, it is not essential to an embodiment of the invention. Any suitable device for movably connecting the end of the arm with the window frame and for guiding the arm in its movements 10 may be substituted for the guide plate and more or less satisfactory results secured.

Having thus fully described our invention, what we claim as new and desire to secure by Letters Patent, is:—

15 1. A device for adjusting a hinged member relatively to a fixed member comprising a guide adapted to be mounted on one of said members, a structure adapted to be mounted on the other of said members and 20 having a bearing, an arm having a part co-operating with said guide and having another part journaled in said bearing, and means mounted in that member having the bearing structure for locking the last-mentioned part of said arm against turning 25 movement in said bearing.

2. A device for adjusting a hinged member relatively to a fixed member comprising a guide adapted to be mounted on one of 30 said members, a socket adapted to be mounted on the other of said members and constituting a bearing, an arm having a part co-operating with said guide, a pivot pin rigidly secured to said arm at a point remote 35 from the part which co-operates with said guide, said pivot pin being journaled in said bearing, and means for locking said pivot pin against rotary movement in said bearing.

40 3. A device for adjusting a hinged member relatively to a fixed member comprising a guide adapted to be mounted on one of said members, a socket adapted to be mounted on the other of said members and constituting a bearing, an arm having a part co-operating with said guide, a pivot pin rigidly secured to said arm at a point remote 45 from the part which co-operates with said guide, said pivot pin being journaled in said bearing, means for locking said pivot pin against rotary movement in said bearing, and other means for supporting said pivot pin in different axial positions relatively to 50 said bearing.

55 4. A device for adjusting a hinged member relatively to a fixed member comprising a guide adapted to be mounted on one of said members, a split sleeve adapted to be mounted on the other of said members, an 60 arm having a part co-operating with said guide, a pivot pin rigidly secured to said arm and journaled in said split sleeve, and means co-operating with said sleeve to clamp 65 said pivot pin within the same or to release said pivot pin, whereby the latter may be

turned to adjusted positions and locked in such positions.

5. A device for adjusting a hinged member relatively to a fixed member comprising a guide adapted to be mounted on one of 70 said members, a split sleeve adapted to be mounted on the other of said members, an arm having a part co-operating with said guide, a pivot pin rigidly secured to said arm and journaled in said split sleeve, and means co-operating with said sleeve to clamp 75 said pivot pin within the same or to release said pivot pin, whereby the latter may be turned to adjusted positions and locked in such positions, said pivot pin having a plurality of annular grooves and a part carried by said split sleeve and adapted to enter any one of said grooves to support said pivot pin in a selected axial position relatively to 80 said sleeve.

85 6. A device for adjusting a hinged member relatively to a fixed member comprising a guide mounted in one of said members and adapted to lie between said members when said hinged member is in its closed position 90 relatively to the fixed member, a socket mounted in the other of said members and constituting a bearing, an arm having a part co-operating with said guide, a pivot pin rigidly secured to said arm and journaled 95 in said bearing, whereby when said hinged member is in its closed position said arm will be moved into a position substantially parallel with said guide and will lie between said hinged member and said fixed member 100 and means for locking said pivot pin against turning movement in said socket.

105 7. A device for adjusting a hinged member relatively to a fixed member comprising a guide mounted in one of said members and adapted to lie between said members when said hinged member is in its closed position relatively to the fixed member, a socket mounted in the other of said members and constituting a bearing, an arm having a part 110 co-operating with said guide, a pivot pin rigidly secured to said arm and journaled in said bearing, whereby when said hinged member is in its closed position said arm will be moved into position substantially parallel with said guide and will lie between 115 said hinged member and said fixed member, and means to lock said arm in adjusted positions relatively to said hinged member to control the position of the latter.

120 8. A device for adjusting a hinged member relatively to a fixed member comprising a guide mounted in one of said members and adapted to lie between said members when said hinged member is in its closed position relatively to the fixed member, a socket mounted in the other of said members and constituting a bearing, an arm having a part co-operating with said guide, a pivot pin rigidly secured to said arm and journaled 125 130

in said bearing, whereby when said hinged member is in its closed position said arm will be moved into position substantially parallel with said guide and will lie between said hinged member and said fixed member, means for locking said pivot pin against turning movement in said socket, and means for supporting said pivot pin in different axial positions relatively to said socket.

9. A device for adjusting a hinged member relatively to a fixed member, one of said members having a recess extending lengthwise thereof, a slotted guide plate mounted in said recess, the other of said members having a recess in the side adjacent said guide plate, a socket mounted in said recess, a pivot pin journaled in said socket, an arm rigidly secured to said pivot pin and having a stud to travel in the slot of said guide plate, said last-mentioned member having a recess extending lengthwise thereof to receive said arm when said hinged member is in its closed position, and means for locking said arm against movement.

10. The combination, with a fixed member having a recess extending lengthwise thereof, a guide mounted in said recess, a hinged member mounted for movement toward and away from said fixed member, said hinged member having a recess in one face thereof, a socket mounted in said recess, a face plate carrying said socket and secured to said hinged member to close said recess, a pivot pin journaled in said socket, an arm rigidly secured to said pivot pin, a stud secured to said arm at a point remote from said pivot pin and coöperating with said guide, and means coöperating with said socket to lock said pivot pin against turning movement in said socket.

11. The combination, with a fixed member having a recess extending lengthwise thereof, a guide mounted in said recess, a hinged member mounted for movement toward and away from said fixed member, said hinged member having a recess in one face thereof, a socket mounted in said recess, a face plate carrying said socket and secured to said hinged member to close said recess, a pivot pin journaled in said socket, an arm rigidly secured to said pivot pin, a stud secured to said arm at a point remote from said pivot pin and coöperating with said guide, and means coöperating with said socket to lock said pivot pin against turning movement in said socket, said pivot pin having a plurality of circumferential grooves, and a pin mounted in said socket and adapted to enter any one of said grooves to support said pivot pin in different axial positions relatively to said socket and to said face plate.

12. The combination, with a fixed member having a recess extending lengthwise thereof, a guide mounted in said recess, a hinged member mounted for movement toward and away from said fixed member, said hinged member having a recess in one face thereof, a split sleeve mounted in said recess, a face plate carrying said split sleeve and secured to said hinged member to close said recess, a screw-threaded stem mounted in said face plate and connected with said split sleeve, a pivot pin mounted in said sleeve and adapted to be clamped against movement by the action of said screw-threaded stem, an arm rigidly secured to said pivot pin, and a stud secured to said arm and coöperating with said guide.

13. A device for adjusting a hinged member relatively to a fixed member comprising a clamping device adapted to be rigidly mounted on one of said members and having a part constituting a bearing, an arm having a part journaled in said bearing, means for actuating said clamping device to lock said part against movement, and means for movably connecting the other end of said arm with the other of said members and for guiding the same in its movements relatively to said other member.

14. A device for adjusting a hinged member relatively to a fixed member comprising a split sleeve adapted to be mounted on one of said members, an arm, a pivot pin rigidly secured to said arm and journaled in said split sleeve, means coöperating with said sleeve to clamp said pivot pin within the same or to release said pivot pin, and a device for connecting said arm with the other of said members and for causing the same to move in a fixed path relatively to said other member.

15. A device for adjusting a hinged member relatively to a fixed member, said hinged member having a recess in one face thereof, a socket mounted in said recess, a plate carrying said socket and secured to said hinged member to close said recess, a pivot pin journaled in said socket, an arm having one end rigidly secured to said pivot pin, means coöperating with said socket to lock said pivot pin against turning movement therein, and a movable connection between the other end of said arm and the fixed member to guide said end of said arm in a fixed path relatively to said fixed member.

In testimony whereof, we affix our signatures in presence of two witnesses.
